GEORGE W. WARFIELD, OF HUDSON, MASSACHUSETTS.

Letters Patent No. 70,139, dated October 22, 1867.

IMPROVED MACHINE FOR SHAPING BOOT-HEELS.

The Schedule referred to in these Letters Patent and making part of the same.

TO ALL-WHOM IT MAY CONCERN:

Be it known that I, GEORGE W. WARFIELD, of Hudson, in the county of Middlesex, and State of Massachusetts, have invented an improved Machine for Shaping or Trimming the Heels of Boots or Shoes; and do hereby declare the following to be a full, clear, and exact description thereof, reference being had to the accompanying drawings, making part of this specification, and in which—

Figure 1 is a side elevation,

Figure 2 a front end elevation,

Figure 3 a plan, and

Figure 4 a vertical and longitudinal section of such machine.

Figure 5 is an under side view of the clamp-plate, and

Figure 6 a perspective view of the heel-receiving former, to be hereinafter described.

This invention is to provide a ready and expeditious means of not only shaping a heel for application to a boot or shoe, but at the same time to prick or indent the tread of the heel as a guide for punching the nail-holes in applying the heel to such boot.

The invention consists in a revolving plate for supporting the heel to be trimmed, and serving at the same time as a former or pattern to regulate the cut of the rotary cutter, the said plate being supported in a suitable frame, and having a mechanism applied to it for clamping the heel to its upper surface, essentially as herein-after described. The invention further consists in forming the clamp-plate, which secures the heel to the "former," with a series of pointers or pins, which impress upon the outer surface of the heel a range of dots or indentations for marking the position of the nail-holes which are to be punched in such heel.

In the accompanying drawings, A denotes the frame of the machine, it being of the proper shape to support the working parts thereof, and being provided with a shelf or operating-table, a, at its upper part. The rotary cutter is shown at B, as supported in journals b b, upheld in bearings made in the upper extremities of the arms e e of a vibrating carriage or head-stock, C, the shaft or base d of such carriage revolving in suitable bearings e e, applied to cross-braces f f, making part of the frame of the machine, the carriage C being pressed forward to the heel-former by a spring suitably applied to the frame A. The mandrel of the cutter B has a pulley, g, fixed to it, around which an endless belt, h, travels, and puts it in rotation, the said belt also extending around a pulley, i, fixed to a horizontal shaft, j, supported by cross-braces k k of the machine frame; this shaft j having a second pulley, l, fixed to its opposite end, around which and a pulley, m, fixed to a driving-shaft, n, an endless belt, o, travels, and puts the said shaft j in rotation. The supporting and shaping-bed or "former" is shown at p as supported upon the upper end of a vertical shaft, q, revolving in suitable bearings made in the frame A, and in a step, r, formed therein; the revolutions of the shaft q and "former" p being effected by a worm-gear, s, fixed to the lower part of such shaft, and which meshes into a worm, t, secured to a horizontal clutch-shaft, u, supported in suitable boxes v v, upheld by the frame A, and revolved by means of an endless belt, w, which passes around a pulley, x, supported by such, shaft and a pulley, y, fixed to the driving-shaft n, before mentioned. The pulley x revolves freely upon the shaft u, and has a semi-clutch, z, formed upon its inner end, which operates in connection with a semi-clutch, a', formed upon the said shaft, as represented in the drawings. The movements of the pulley x and semi-clutch z are controlled by a shiftable-lever, b', the fork of which spans the arbor of such pulley, and whose upper end extends through a slot, c', made in the table of the machine, and is provided with a handle, d', for readily operating it. The fulcrum of this lever p' is a staple, e', suitably applied to any contiguous part of the frame A. A sliding cross-head, f', surrounds the "former" p, and is supported by two vertical rods g' g', whose lower ends are secured to and sustained by a cross-bar or carriage, h', which in turn is supported upon the upper end of a rod, i', the lower end of such rod being fixed to a treadle, j', attached to a rocker-shaft, k', upheld by the frame A. A clamp-plate, l', is disposed above the "former" p, and is upheld by a revolving stud, m', depending from the cross-head f', as shown in fig. 4 of the drawings. The under side of this clamp-plate l' has a series of points or pins n¹ n¹ n¹, etc., arranged upon it, as shown in figs. 4 and 5. A spiral spring, a², encircles each the upper part of each of the rods g' g', and between the table a and the cross-head f', these springs serving to force such cross-head upward, and raise the clamp-plate l' from off the "former" p. The shape of this former or cam plate is given

in fig. 6 of the drawings as approximating to that of an oval, the larger part, n^2 , of such former being the required shape to be imparted to the heel. The pointed or elongated portion o' of such former is for the purpose of pressing against the side of the carriage C, and forcing the cutter B away from such former, and from the heel placed upon it after the curved portion of such heel has been trimmed into shape by the cutter. A stop, p' , is formed upon the upper surface of the former p , as shown in the said fig. 6, and serves as a gauge or abutment for the inner or flat edge of the heel to rest against, as well as to guide and retain the clamp-plate in its due relation to such former, and cause it to revolve with it. The axis of the shaft of the cutter B should be such a distance above the surface of the former p as to give the necessary angle to the sides of the heel. To accomplish this the shaft q may be provided with a set-screw, a^4 , at its bottom, for raising and lowering it.

In operating with the above-described machine, the heel, having previously been formed nearly into proper shape, is to be placed upon the upper surface of the former p , and with the flat or front edge of such heel in contact with the stop p' , the point of said former being in the position shown in fig. 4 of the drawings, as pressing the cutter B away from contact with it. The foot of the workman is next to be pressed upon the treadle j' , and the clamp-plate l' forced down upon the heel, which will not only securely hold such heel in place upon the former, under the action of the cutter, but by means of its points n^1 n^1 n^1 will indent the tread of the heel with the necessary line of dots for marking the position of the nail-holes. The handle of the shiftable-lever b^1 is now to be pressed inward, which throws the two portions z and a' of the clutch into engagement with each other. The revolutions of the pulley y in the direction of the arrow thereon will cause corresponding revolutions of the worm t . These revolutions of the worm t put the worm-gear s in rotation, and with it the "former" p . As the pointed portion o' of the former p recedes from the front face of the carriage C, or a ledge or guard b^2 applied to its front part, the remaining portion of the former brings up against such guard b^2 , and brings the heel in contact with such cutter. The "former" continues to rotate, and subject the heel to the action of the cutter until it has completed one revolution, and its cam or point o' again brings up against the cutter-carriage and forces the cutter away from such heel. At this point the clutch is to be disengaged, which will stop the motion of the "former" and allow the heel to be removed after releasing the pressure upon the treadle.

I claim—

1. The employment of the revolving cam-plate or former p for the purpose both of supporting the heel and giving the required outline to it, under the action of the rotary cutter, substantially as hereinbefore described.
2. I claim, in combination with such cutter B, and in a machine for trimming boot-heels, the fender or ledge b^2 , applied to the cutter-carriage C as set forth and explained.
3. I claim the construction and mode of application of the clamp-plate l' , in manner, and operated by the treadle j' , as before explained.
4. I claim the peculiar construction of the "former" p , as composed of the oval-shaped plate for giving the necessary movements to the cutter-carriage C, and of the stop or abutment p' , as and for the purpose set forth.
5. I claim the general combination and arrangement of the machine as herein shown and described, consisting of the revolving cutter B, the "former" p , and the clamp l' , these several parts being operated by their respective mechanisms in manner as before referred to and explained.

GEO. W. WARFIELD.
